UNITED STATES PATENT OFFICE

165,791

FABRIC

Henry Rose, New York, N. Y.

Application December 12, 1950, Serial No. 13,387

Term of patent 7 years

(Cl. D92—1)

To all whom it may concern:

Be it known that I, Henry Rose, a citizen of United States of America, resident of New York, in the county of New York, and State of New York, have invented a new, original, and ornamental Design for a Fabric, of which the following is a specification, reference being had to the accompanying drawing, forming part thereof.

In the drawing

Figure 1 is a plan view of a fabric, showing my new design; and

Figure 2 is a plan view on an enlarged scale of a portion of the design unit.

The design comprises a cloudy striped effect background with intermittent groups of single dots superposed thereon, said dots being aligned parallel to the background stripe effect. A group of dots of any one color is offset with respect to the next adjacent group of corresponding color dots and separated therefrom by intervening strips of contrasting groups of dots. The groups of dots are arranged in the design unit as shown.

Said design unit is repeated over the fabric as illustrated.

I claim:

The ornamental design for a fabric, substantially as shown and described.

HENRY ROSE.
